United States Patent Office

Des. 221,353
Patented Aug. 3, 1971

221,353

DIFFERENTIAL

Hans Hauser, Fredericktown, Ohio, assignor to The J. B. Foote Foundry Co., Fredericktown, Ohio

Filed Mar. 5, 1970, Ser. No. 21,758

Term of patent 14 years

Int. Cl. D15—99

U.S. Cl. D55—1

Fig. 1

Fig. 2

Fig. 3

Fig. 4

FIG. 1 is a front view in elevation of a differential showing my new design;

FIG. 2 is a left hand end view of the differential;

FIG. 3 is a right hand end view of the differential; and
FIG. 4 is a top view of the differential.

What I claim is:

The ornamental design for a differential, substantially as shown and described.
